UNITED STATES PATENT OFFICE.

AMELIA B. WELLS, OF NEW YORK, N. Y.

DESIGN FOR A LADY'S GARMENT.

54,155.

Specification for Design.

Patented Nov. 4, 1919.

Application filed June 6, 1918. Serial No. 238,619. Term of patent 7 years.

To all whom it may concern:

Be it known that I, AMELIA B. WELLS, a citizen of the United States, residing at New York city, in the borough of Manhattan, county and State of New York, have invented a new, original, and ornamental Design for a Lady's Garment, of which the following is a specification, reference being had to the accompanying drawing, forming part thereof.

Figure 1 is a perspective view showing the garment as it appears viewed from the front and Fig. 2 is a perspective view of the same viewed from the back.

My new design covers broadly a lady's garment which is given a highly ornamental

and artistic effect by the particular shape and disposition of a girdle or sash A dropping from a point below the shoulder in the rear of the garment to the front of the garment near the hip where the artistic effect is completed by the portion B completing the girdle at the waist line and of varying width, curving down gradually from the highest point C toward the sides.

I claim:

The ornamental design for a lady's garment as shown and described.

AMELIA B. WELLS.
